SHINGLE CONSTRUCTION

Charles M. Vibert, Oak Park, Ill.

Application September 29, 1945, Serial No. 619,297

8 Claims. (Cl. 108—9)

1

The invention relates generally to a shingled roof construction and more particularly to composition shingles such as the so-called asphalt type.

The general object of the invention is to provide a novel shingle roof construction which prevents the shingles from being forced upwardly at their free or lower edges, away from the underlying shingles.

Stated in different words, the general object is to provide a novel shingle construction which, when laid on a roof, permits the shingles to lie flat.

It is also an object to provide a novel shingle construction which may be readily laid, which facilitates placing of the shingles so as to obtain accurately aligned and spaced rows, and which reduces the time required to cover a roof.

Other objects and advantages will become apparent from the following description taken in connection with the accompanying drawings, in which:

Figure 1 is a fragmentary view of a shingled roof construction utilizing a standard commercial type of shingle.

Fig. 2 is an enlarged sectional view taken on the line 2—2 of Fig. 1.

Fig. 3 is a view similar to Fig. 1, but utilizing shingle units embodying the features of the invention.

Fig. 4 is an enlarged sectional view taken on the line 4—4 of Fig. 3.

Fig. 5 is a fragmentary enlarged sectional view taken on the line 5—5 of Fig. 3.

The usual roof construction where shingles are employed includes sheathing, indicated generally at 8, laid on rafters (not shown). The sheathing 8 ordinarily comprises a plurality of boards 9 extending horizontally or crosswise of the roof, the boards preferably having a tongue and groove construction 10 and being laid tight and nailed to the rafters. The sheathing 8 may be covered with a coated building paper (not shown), and the shingles are then laid over the paper and nailed to the sheathing.

Composition shingles, such as the so-called asphalt shingles, are commonly used in present construction, and such shingles are frequently provided in sets of three formed from an integral strip or member of composition material. Each strip is provided with slots 11 extending upwardly from the lower edge of the shingles to divide the strips into the respective shingle sections so that when the roof is laid each section appears to be a separate shingle. When such shingles are laid

on the sheathing, the common practice is to nail them thereto by a horizontal line of nails 12 positioned above the slots 11 in such location in the shingle that they will be covered by the next upper row of shingles. Thus, in Figs. 1 and 2, I have shown four rows of such shingles, respectively indicated at 13, 14, 15 and 16.

As is customary, the shingles in any row are offset laterally relative to the shingles in the adjoining rows, substantially one half the width of each individual shingle, so that the abutting edges of the strips or members will be partially covered by the next upper row of shingles. The vertical overlap of the shingles is usually slightly more than one half of the length or height of each shingle. Thus, when the nails 12 are applied, as shown in Figs. 1 and 2, each line of nails extends not only through the shingle through which it is initially driven, but also through the shingle in the row next below it, except of course in the case of the bottom row of shingles. Thus, as is clearly apparent from Fig. 2, each row of shingles is secured by two lines of nails.

While I have shown herein shingles of rectangular form, a similar construction is used in the case where octagonally shaped shingles are employed, that is, shingles which produce an octagonal design on the roof when laid.

After a roof has been laid, it has frequently been noted that the shingles are forced upwardly so that their lower edges or flap portions are lifted above the underlying shingles in the next lower row, giving an uneven and unsightly appearance to the roof because of the irregularity of such lifting. Such lifting also tends to cause deterioration of the roof since it permits wind to get under the shingles and tends to tear them off. Moreover, it is obvious that rain, particularly in a driving storm, can be forced under the shingles when they are lifted in this manner. This fault has been noted particularly in the case of roofs laid on newly constructed houses.

To determine the cause of such difficulty, carefully conducted tests have been made to determine whether there is any material shrinkage and expansion of shingles of this type, and the results showed that change in dimensions due either to temperature changes or to moisture changes was negligible. Attention was, therefore, directed to the underlying structure of the roof to consider what occurred in that portion of the structure, and particularly in the boards constituting the sheathing.

It is a fact that wood boards have some con- traction and expansion lengthwise of the grain,

but such change of dimension is very small. However, the change of dimension transversely of the grain, due to change in moisture condition of the wood, is considerable. Thus, it has been found that dimensional changes longitudinally of the grain amount to only a small fraction of 1 per cent, while changes in dimension transversely of the grain may go as high as 12 per cent, depending upon how the wood is cut.

In constructing the roof of a newly built house, much shrinkage of the sheathing boards may occur if the boards have not been properly seasoned or dried previous to laying. Moreover, the sheathing boards may absorb considerable moisture at the time they are laid, since a rain may occur between the time when the sheathing boards are applied and the time when the shingles are laid. Expansion of the heathing boards by the absorption of moisture may also occur since the plastering of a house is frequently performed soon after the roof is laid, so that the moisture emanating from the plaster during its drying may be absorbed by the sheathing boards.

If the shingles are laid on the sheathing board at the time that they contain a large quantity of moisture, there will obviously be considerable shrinkage in such boards as the house dries out, and it has been determined that such shrinkage is one of the chief causes of causing the lower edges or flaps of the shingles to be lifted. Thus, as illustrated in Fig. 2, with each shingle nailed to the sheathing boards by two rows of nails 12, shrinkage of the sheathing boards will tend to buckle each shingle in the portion, indicated at 20, between the rows of nails, since the shingle itself is not subject to such shrinkage. Each portion 20 is in the upper part of the shingle and, therefore, is overlapped by the lower or flap portion of the shingles in the next upper row. This causes a lifting of such flaps or lower portions, which effect is multiplied because of the fact that the flap extends downwardly beyond the bulge portion 20. Thus, each row of shingles, except for the bottom row, will tend to be lifted at its lower edge, the amount of lifting varying in different portions of the rows with the variation in moisture change of the sheathing boards. An unsightly appearance will, therefore, result from this construction. This difficulty is particularly pronounced where two rows of nails are driven into the same sheathing board.

Expansion of the sheathing boards due to the absorption of moisture after the shingles are laid causes a similar difficulty. Thus, when expansion occurs, the distance between the two rows of nails in each shingle is increased. Since the nails in one horizontal line are staggered with relation to the nails in the next horizontal line, there is an angular pull on each shingle which tends to cause a bowing or budging of each shingle in a transverse direction crosswise of the roof, that is, the lower edge of each shingle will tend to bow upwardly between its side edges.

The present invention provides a shingle construction which eliminates these difficulties and permits the shingles to lie flat regardless of the change of moisture content and shrinkage or expansion of the sheathing boards. To attain this end, I provide a shingle construction in which each shingle is secured to the sheathing boards 9 by only one line of nails. Thus, changes in width of the sheathing boards due to shrinkage and expansion from change of moisture content will not affect the shingles since the shingles and sheathing boards may shift relative to each other

in the plane of the roof except at the line of nailing. There is, therefore, no tendency of the shingles to bulge upwardly from the plane of the roof.

To permit the shingles to be laid with only one line of nails through each shingle, I arrange the shingles in pairs with one shingle in one horizontal row and the other shingle in an adjoining row. Thus, as illustrated in Figs. 3 and 4, the shingle indicated at 21 is paired with the shingle indicated at 22, while shingles 23 and 24 in the next two rows above are paired. The two shingles of each pair are secured together independently of the sheathing and prior to laying, and consequently such securing may be performed as a step in the manufacture so that a firm bond may be obtained therebetween. Preferably, the two shingles of each pair are constructed in the ordinary manner and then are adhesively secured together, the two overlapping in the normal relationship heretofore utilized, that is, both horizontally and vertically overlapped to the same extent that the shingles are overlapped in the usual construction such as is shown in Figs. 1 and 2. The pairs of shingles are then laid upon the sheathing boards 9 and secured thereto with a single horizontal line of nails 25. Such line of nails is positioned adjacent the upper edge of the lower shingle of each pair so that it will be spaced above the upper edge of the next lower row of shingles, and also so that it will underlie and be covered by a shingle in the row above the pair. Thus, with any shrinkage or expansion of the sheathing boards, there will be no bulging of the shingles since the shingles are free of the sheathing boards except along the line of nails 25.

Each pair of shingles which have been preconnected as herein described may be considered as a unit, and the units in a given row may be overlapped by the units in the next upper row to the extent and in the same manner as the two shingles of each pair or unit. Thus, when the roof is laid there is no difference in appearance between the relation of two shingles of one unit or pair and the relation of two shingles of different units. The lower shingle of each pair or unit, while secured by the nails 25 only adjacent its upper edge, is reinforced and held flat against the roof by the upper shingle of that pair so that the lower shingle of each pair will lie substantially as tight to the roof as in the ordinary shingle construction.

While a shingle construction embodying the invention may involve the cementing together of two individual shingles, strips or members provided with the slots 11 in their lower edges to form a plurality of shingles may be similarly cemented together to thus embody the features of the invention. The shingles 21, 22, 23, and 24 are each one of the shingles formed in such strips or members. Also, shingles of the octagonal or other types may be formed in units in a similar manner.

If it is desired to provide more secure fastening for the lower shingle of each pair or unit, such lower shingle may be attached to the upper shingle in the unit next below in a manner that will permit relative shifting of the two shingles in the plane of the roof but will prevent the overlying shingle from being lifted. To this end, a U-shaped metal clip 30 (see Fig. 5) of a form heretofore employed in the art may be utilized. For example, a clip 30 may be inserted with one end of the U underlying the shingle 22 at the

upper end of slot 11 and the other end overlying the lower edge of the shingle 23 to tie it down. Said other end of the clip is provided with a sharp point adapted to be driven into shingle 23 but the end underlying the shingle 22 has no such point, so that relative shifting of the two shingles in the plane of the roof may occur. Instead of the clips 30, the lower shingle of each pair or unit may be attached to the upper shingle of the next lower unit by a cement applied at the time of laying the roof and of a character which remains relatively soft to permit the desired shifting in the plane of the roof.

From the foregoing, it will be evident that I have provided a novel roof construction and shingle therefor, which permits the shingles to lie flat regardless of shrinkage or expansion of the underlying sheathing. Since each shingle is secured to the sheathing by only one horizontal line of nails, it is free to shift in the plane of the roof relative to the sheathing, except at the line of nails, so that shrinkage or expansion of the sheathing cannot cause any bulging of the shingles. The construction facilitates laying the shingles and, since shingles in two rows are laid at the same time, the time required to lay the shingles is materially reduced.

While the foregoing description and the following claims refer to a shingle roof construction, the invention is not limited specifically to a roof but may also be embodied in a shingled side wall construction.

I claim:

1. A shingled roof construction comprising sheathing boards extending horizontally of the roof, and overlapping horizontal rows of shingles laid on said sheathing boards, said horizontal rows being adhesively secured together in pairs, and each pair being nailed to the sheathing on a horizontal line located above the next lower row of shingles and under the next upper row, whereby each row of shingles is secured to the sheathing by only one row of nailing.

2. A shingled roof construction comprising sheathing boards extending horizontally of the roof, and overlapping horizontal rows of shingles laid on said sheathing boards, the shingles in each horizontal row being secured to the shingles of one of the adjoining rows independently of the sheathing to provide interconnected pairs of shingles respectively lying in adjoining rows, and each pair being nailed to the sheathing along a horizontal line located above the upper edge of the next lower row of shingles and under the lower portion of the next upper row and also in the overlapping portions of said pair, whereby each shingle is secured to the sheathing by only one row of nailing.

3. A shingled roof construction comprising sheathing boards extending horizontally of the roof, and overlapping horizontal rows of shingles laid on said sheathing boards, said horizontal rows comprising preconnected pairs of shingles respectively lying in adjoining rows with each pair secured to the sheathing on a single horizontal line located in spaced relation to the next lower row of shingles and covered by the next upper row.

4. A shingled roof construction comprising sheathing boards extending horizontally of the roof, and overlapping horizontal rows of shingles laid on said sheathing boards, each horizontal row comprising a plurality of shingle members each composed of a plurality of integrally connected shingles, each member being secured to a member

in an adjoining row independently of securing the members to the sheathing, and each pair of members so secured being nailed to the sheathing on a single horizontal line located in the overlapping portions of each member of the pair and spaced above the next lower row, said line being covered by the next upper row.

5. A shingled roof construction comprising sheathing boards extending horizontally of the roof, overlapping horizontal rows of shingle members laid on said sheathing boards, each member having one or more slots extending upwardly from its lower edge to simulate a plurality of shingles, and each member being secured in overlapping relation to a member in an adjoining row independently of securing the members to the sheathing, each pair of members so secured being nailed to the sheathing on a single horizontal line located above the next lower row and under the next upper row, and clips positioned in the upper ends of the slots in the upper members of the pairs for holding the lower edges of the next upper row against movement perpendicular to the roof but permitting relative movement in the plane of the roof.

6. A shingled roof construction comprising sheathing boards extending horizontally of the roof, pairs of shingles adhesively preconnected in vertically overlapping relation, with the pairs laid on said sheathing boards to form horizontally extending rows, each of said pairs being nailed to the sheathing along a single horizontal line located in the overlapping area of the pair above the next lower row and under the next upper row, the lower shingle of each pair being yieldingly cemented to a shingle in the next lower row.

7. A roofing shingle unit comprising a pair of members each having one or more slots extending upwardly from its lower edge to simulate a plurality of shingles, the pair of members being partially overlapped to an extent equal to the normal overlapping of two rows of shingles and being horizontally offset to position the slots in the upper strip intermediate the slots in the lower strip, the overlapping portions of the two strips being adhesively secured together to form the unit, the unit being adapted to be secured to the roof by a single row of nails located in the overlapping area of the two strips and adjacent the upper edge of the lower of the two strips.

8. The method of roofing which comprises adhesively securing pairs of shingles together laterally and lengthwise overlapped to an extent equal to the normal overlapping of shingles when laid, laying said pairs on the roof in horizontal rows, with the lower shingles of the pairs in one row overlapping the upper shingles of the pairs in the next lower row to an extent equal to the overlapping of the shingles in each pair, and nailing each row of pairs along a single horizontal line in the overlap of the shingles of each pair and spaced above the upper edge of the upper shingles in the next lower row and under the lower shingles in the next upper row.
